TUBE ROLLING MILL

Martin Roeckner and José Severin, Mulheim-on-the-Ruhr, Germany, assignors to Deutsche Röhrenwerke Aktiengesellschaft, Dusseldorf, Germany

Application May 28, 1938, Serial No. 210,723
In Germany July 14, 1937

3 Claims. (CL 80—13)

This invention relates to a tube rolling mill for producing seamless tubes. It is known to produce tubes by subjecting a hollow block to the action of several pairs of rolls which are arranged around the block at a certain distance from the axis of the hollow block, one roll of each pair of rolls acting on the inner side and the other on the outer side of the wall of the block. The rolls have different profile developments by which a groove is cut in the material of the hollow block by the first pair, this groove being widened by the next following pair so that a portion of the material divided off by the first pair is gradually drawn out towards one end of the hollow block. The axes of the rolls are at an incline to the axis of the hollow block and thus not only exert a deformation, elongation, but also a feed movement like a worm gear. However, the feed movement of the hollow block takes place only at the commencement of the deformation. Now it has been found objectionable, that the hollow block to be rolled has to be pushed by some external auxiliary means between the rolls which have to carry out the deformation work. For overcoming this objection it has been proposed, to provide the rolls at the feed end with a relatively long slightly tapering portion which is intended to better draw the material into the rolls. Another proposal is, to taper that end of the hollow block which is pushed into the rolling mill, so as to facilitate under all circumstances, a displacement of the hollow block in longitudinal direction.

In these known proposals it is consequently necessary to specially shape either the rolls or the hollow block. Another roll arrangement is proposed, according to the invention, which allows a perfect drawing in of the hollow blocks by the rolls, without it being necessary to alter the ordinary shape of the rolls or of the hollow blocks. Consequently, the ordinary blocks with the usually smooth cut edge can be rolled without difficulty. This is attained in that according to the invention the rolls are mounted so that they can yieldingly shift in a longitudinal direction to such an extent that when drawing in the hollow block, the ribs of several successively acting rolls are adapted to lie in front of the block whereby the working or drawing of the ribs into the hollow block is insured. This can be attained by displacing the rolls in the longitudinal axial direction against the action of springs or weights, this displacement being moreover adjustable. The normal rolling operation or process is also favorably influenced by said yielding capacity of the rolls.

Referring to the drawings:

Figures 1 and 1a show, for a clear understanding of the distinction between the known art and the invention, working rolls heretofore used; Figure 1 being a side elevation and Figure 1a a sectional view taken on the line A—B of Figure 1.

Figure 2 is a side elevation of one of the rolls and showing the manner in which said roll can be displaced on its axis against the action of a spring.

Figures 3 and 4 are side elevational views of constructional examples for regulating the extent of the longitudinal displacement of the rolls.

Figs. 5, 6 and 7 are diagrammatic views showing the various stages of the rolling operation, 15 carried out with the use of the rolls shown and described in conjunction with Figs. 2, 3 and 4.

In the known process, as illustrated diagrammatically in Figs. 1 and 1a, the inconvenience exists that the hollow block is not gripped by the 20 rolls 1—1, 2—2, 3—3. This is due to the following reason. When the slightly tapered portion of the rolls first grips the block and commences to draw it in, the block first encounters the rib of the roll 1 which tends to arrest the block. 25 However, it overcomes this obstacle and moves on until it encounters the rib of the roll 3 which tends to arrest the block. As all the compressing ribs are situated on a helical line, the block in order to strike against the ribs of the different 30 rolls must shift a short distance from rib to rib. This short distance, however, does not allow the shaping of a recessed portion of material. The first rolls have no grip behind their ribs and the block can consequently not move on.

With the roll arrangement according to the invention (Figs. 2, 3 and 4), that is when the rolls are movable in the direction of their longitudinal axis, one roll can roll into the block after the other, in that owing to its inclined position it shifts forward, whereas the following rolls are pushed backwards against the action of the spring 4 (Fig. 2) by the block and thus sufficient space is produced between the ribs of the first and second rolls, whereby a material portion of the block in the space between each roll will be gripped and drawn in between the rolls. The longitudinal displacement of the rolls is preferably effected by the action of the hollow block pressing thereagainst, and as shown in Fig. 2, 40 said rolls are displaced on their axes against the spring 4. This displacement of the rolls is adjustable according to the constructions illustrated in either Figs. 3 or 4. This may be effected as shown in Fig. 3, by connecting the roll with an 45 50 55

externally screw threaded sleeve 5 provided with a worm wheel 6 adapted to be actuated by a worm 7. By actuating the worm 7, the roll may be adjusted in a position toward or away from the 5 spring 4, depending on the amount of longitudinal displacement desired for the rolls.

Another manner of adjusting the longitudinal displacement of the rolls is shown in Fig. 4, wherein the roll bearings are carried in brackets 10 8 which are shiftable by a spindle 9 with screw thread 10 so that the rolls are shifted in the direction of their longitudinal axis.

Referring now more particularly to Fig. 5, this 15 shows diagrammatically the movement of the rolls relatively to the hollow block when the front edge of the hollow block bears against the rib of the first roll.

Fig. 6 shows diagrammatically the hollow block 20 when the latter has been drawn forward to such an extent that its front edge bears against the rib of the third roll, the illustration in this view in full lines of the rolls 1 and 2 shows these rolls in the position which they occupy when their 25 ribs have been drawn into the surface of the hollow block. The illustration in dotted lines in Fig. 6 shows the position of the rolls 1 and 2 when they have not been drawn into the block, but are pushed back in their longitudinal direction by the front edge of the hollow block against the action 30 of the spring shown in Fig. 2.

Fig. 7 shows diagrammatically the position of the rolls during the normal rolling operation after all the rolls have been moved back into their forward position by the spring 4.

35 It is evident, that the displacement and the adjusting of the displacement may be effected in any other way than described and illustrated without departing from the scope of the invention.

It is to be noted that the profile development of the working surfaces of the second pair of rolls and each successive pair of rolls have for their object to participate in the deformation and elongation of the portion of the material divided off 5 in the form of a rib of the hollow block until the disappearance of the rib and the formation of the smooth cylindrical tube wall which is however thinner than that of the hollow block which lies in front of the first pair of rolls.

10 We claim:

1. A rolling mill for rolling hollow blocks into seamless tubes by elongation chiefly in the axial direction, including several pairs of ribbed rolls inclined to the axis of the hollow block and 15 adapted to form helical lines on the surface of said hollow block, said rolls having successive profile developments so that each following roll further works the part of the hollow block already worked by the preceding roll, said rolls 20 being displaceable in their longitudinal direction to such an extent that when drawing in the hollow block, the ribs of several successively acting rolls are adapted to lie in front of the block so that the yielding capacity of the rolls facilitates 25 the rolling operation.

2. A rolling mill as claimed in claim 1, in which each roll is displaceable in the direction of its longitudinal axis against the action of a spring.

3. A rolling mill as claimed in claim 1 in which each roll is displaceable in the direction of its longitudinal axis against the action of a spring, and including means for regulating the longitudinal displacement of each roll.
